UNITED STATES PATENT OFFICE

RALPH L. SKINNER, OF DETROIT, MICHIGAN

INTERNAL-COMBUSTION ENGINE

Application filed July 10, 1929. Serial No. 377,260.

My invention concerns certain structural and functional features of novelty and advantage in internal-combustion engines, more particularly those of the sliding valve type, 5 as distinguished from the poppet-valve style, whereby to more effectively seal the cylinders and their associated mechanical elements against loss of compression or leakage of gas pressure, to secure more efficient scavenging 10 of the cylinders of the exhaust or exploded gases with resulting diminution of dilution of the new charges of fuel mixtures, to so shape, arrange and combine the mechanical parts to avoid detrimental operating results 15 due to the heating, expansion, etc., to make the valves and their actuating devices of such form and manner of action as to produce improved performance of the engine as a whole, and to obtain other objects and purposes 20 which will be understood from a consideration of several embodiments of the invention illustrated in detail in the accompanying drawings, forming a part of this specification, and throughout the several views of 25 which like reference numerals, for simplicity, have been used to designate the same parts throughout the views.

In these drawings:

Figure 1 is a nearly central, longitudinal, 30 vertical cross-section on line 1—1 of Figure 3 through a portion of one cylinder of a multi-cylinder internal-combustion engine incorporating the features of the present invention;

Figure 2 is an enlarged part only of Figure 1;

Figure 3 is a horizontal section on line 3—3 of Figure 1;

Figure 4 is a horizontal section on line 4—4 of Figure 1;

Figure 5 is a similar section on line 5—5 of Figure 1; and

Figures 6, 7 and 8 are fragmentary sections showing slightly modified constructions of the sealing-reed.

Referring to these drawings, it will be seen that the engine includes a water-jacketed, outer cylinder 22 having a single or uninterrupted fuel-inlet port 23 and an opposite, continuous or single, unbridged, wider exhaust-port 24, the top of the cylinder being

closed by a demountable, depressed head 25 accommodating the usual spark-plug 26, such head being covered by a housing or casing 27 providing a water-jacket or cooling space between them.

Such cylinder, with its like companions of the multi-cylinder engine, is mounted on their common crank-case 28 enclosing the usual crank-shaft 29 and its bearings and the usual supply of lubricating oil.

Inside of such outer cylinder, spaced inwardly therefrom, and with its upper end terminating just below the cylinder-ports 22 and 24, a smaller, inner, stationary cylinder or sleeve 31 is provided being sustained or held in place solely from its lower end by screws 32, 32 engaging threaded holes in supporting means or lugs 33 depending from the cylinder-casting 21 into the crank-case, and, within such inner cylinder, a piston 34 reciprocates being connected in the usual manner to the crank-shaft 29 by a connecting-rod 35.

A comparatively-narrow, longitudinally-split, expansible and contractible sealing-ring 36 bears on the plane or flat, upper end of such inner cylinder and has a bridged or divided inlet-port 37 therethrough in substantial register with, and of practically the same size as, said cylinder inlet-port 23, and a single, unbridged or unstrutted, continuous exhaust-port 38 of practically the same dimensions as the exhaust-port 24 of the outer cylinder, such sealing-ring exhaust-port being therefore wider than its inlet-port.

The over-lapped joint 39 of the split in the sealing-ring is located in the central bridge or strut of its intake-port, all as is clearly shown in Figure 3.

A semi-circular, ported, inlet-valve 41, having a bridged intake-port 42 of approximately the same dimensions as the admission-ports of the outer cylinder and sealing-ring, 23 and 37 respectively, and a companion, semi-circular, ported exhaust-valve 43, having an unobstructed or unbridged discharge-port 44 of practically the same length and width as the delivery-ports 24 and 38 of the cylinder and sealing-ring, and hence wider than the intake-port 42, are located between,

and are slidable lengthwise of, the outer cylinder on the outside and the inner cylinder 31, sealing-ring 36 and cylinder-head 25 on the inside.

- 5 Inlet-valve 41 is reciprocated in proper timed relation to the operation of the other parts of the mechanism by a connecting-rod 45 hinged at 46 to a lug 47 on the lower end of the valve, the other end of the rod being 10 rockingly mounted on an eccentric or crank pin 48 of a horizontal, valve-operating shaft 49 disposed lengthwise the group of engine-cylinders and revoluble in suitable bearings of which only one 51 is shown, such inlet-15 valve shaft being rotated from the main, engine crank-shaft by any suitable mechanism, not deemed necessary to show.

In similar manner, the exhaust-valve 43 is reciprocated by a comparable connecting-rod 20 52 actuated by a crank or eccentric pin 53 of a properly mounted and rotated shaft 54 on the side of the cylinders opposite the location of the inlet-valve shaft 49, the throw or eccentricity of the pin 53 being greater than 25 that of pin 48, whereby the stroke of the exhaust-valve is longer and more rapid than that of the inlet-valve, the two shafts being rotated at the same speed.

It is to be noted, that, in both instances, the 30 path of vertical travel of the axis of the pivotal connection of the connecting-rod with the valve is offset inwardly of the axis of the corresponding shaft 49 or 54 and that the two shafts rotate at the same speed in the 35 same direction and not in opposite directions, for a reason hereinafter stated.

The piston and valves are lubricated in any approved manner, as by the well-known 40 splash system by means of the oil in the crank-case thrown up by the revolving cranks, and, to facilitate the distribution of the oil over the surfaces of the cylinders, valves and cylinder-head, the valves are provided on their outer faces at 55 with any appropriate arrangement of oil channels, the outer surface of the inner cylinder having oil grooves 56 and the surface of the head having similar channels 57.

To aid or assist the entrance of oil between 50 the surfaces of the inner cylinder and the valves, the former is provided with a row of holes 58 therethrough in such a position that, at the end of the down stroke of the piston, the oil wiped off of the inner cylinder 55 by the piston-rings will naturally flow more or less through these apertures to the inner surfaces of the valves.

In order to maintain the sealing-ring at all 60 times in proper engagement or bearing relation with the end surface of the inner cylinder with which it is in contact, and to assist in keeping the sealing-ring joint from leaking, an endless hold-down ring 59 is provided just above, and bearing directly on, the top, 65 flat, end face of the sealing-ring, such mem-

ber 59 being relatively thin and having a bottom, marginal, inwardly-projecting ledge, flange, or lip 61 on which the gaseous pressure in the cylinders act, tending to press the ring as a whole down on the sealing-ring.

Above such internal, bottom ledge, the hold-down ring is slidably, yet movably, accommodated between the two semi-circular valves and an outstanding, circular rib 62 on a lower, reduced-diameter part 63 of the cylinder-head 25.

Gas pressure in substantial amount is not always present in the cylinders to force the hold-down ring sufficiently firmly on the sealing-ring, especially during the upward travel of one or both valves, and, accordingly, supplemental, mechanical means are employed to cooperate with the action of the ring ledge.

To this end, a divided or sectional ring 64, 85 having a plurality of round cavities 65 in its upper surface, is located above and overlies the top end of the hold-down ring 59, being located between a shoulder 66 on the cylinder-head and the rib 62 thereof.

Each pocket 65 houses a short, coiled spring 67 bearing at its upper end against the cylinder-head surface or shoulder 66 and at its lower end against the bottom wall of its cavity, whereby such springs unitedly and 95 conjointly tend to press the hold-down ring on to the sealing-ring and the latter on to the end of the inner cylinder.

Inasmuch as the more or less open, unstrutted or unbridged exhaust-port portion 100 of the sealing-ring is incapable of withstanding as much downward pressure thereon as the other parts of the ring without collapsing, and, since such exhaust-port section of the ring requires such a force acting thereon 105 to hold the sealing-ring in place without rising from its seat on the inner cylinder during the upward travel of the exhaust-valve on which it bears, an excess pressure is exerted by the springs on the other parts of the ring, 110 thus keeping the latter, as a whole, against improper shifting or undesired movement.

Wherefore, a greater number of the springs 67, twice as many in the present instance, are used over the intake-port and adjacent portions of the sealing-ring than are employed over the exhaust-port part thereof, thus in a measure compensating for the absence of a full complement over the exhaust-port section.

It is desirable to prevent leakage or the escape of gas pressure from the cylinders up past the hold-down ring, and, of course, it is also of advantage to preclude the hot combustion or cylinder gases from reaching these little springs.

For the accomplishment of this, an endless, circular sealing-reed 68 is fitted tightly over the lesser-diameter section 63 of the cylinder-head and it bears against the under face of the

5 circular-rib 62, thus assuring that no gas can escape between the reed and head, the former also having a thin, outwardly-flaring, depending, flexible or elastic flange 69 pressing firmly against the inner face of the hold-down ring 59.

10 The normal external diameter of the flange 69 is slightly greater than the internal calibre of the hold-down ring so that when they are assembled in the manner shown there is an 15 actual metal to metal contact between the reed lip and the confining hold-down ring.

15 The natural tendency of expansion of such a lip or flange and the gas pressure in the cylinder which has free access thereto, promoting its expansion or outer flexure into sealing engagement with the hold-down ring, assures prevention of leakage of pressure between them.

20 To assist in sealing, closing or covering the joint between the sealing-ring and the inner cylinder, a thin, flexible, metal gland 71 may be employed to overlap the two, contacting members involved, such element being held 25 in place by means of its outstanding flange 72 occupying and snugly fitting in a circular groove in the inner face of the sealing-ring.

25 In similar manner, the joint between the sealing and hold-down rings may be protected 30 by a second, like gland 73.

30 In both instances, the gas pressure in the cylinders expands the glands slightly and presses them firmly against the elements which they overlie or overlap, thus effectively 35 sealing or closing the joints between the members.

35 As a further means of insuring the maintenance of pressure and compression tight relations between the sealing-ring and the inner cylinder, the hold-down ring, and the valves, the sealing-ring is provided in its face 40 in engagement with the end of the inner cylinder with an oil groove 74, in its surface in contact with the hold-down ring with a similar lubricant groove 75, and in its outer, curved surface bearing on the sliding valves with similar grooves, 76, 76 located above and below the ports of the ring.

45 In such instance, the ends of the groove or channel terminate slightly short of, and do not intersect, the sealing-ring joint.

50 Oil collects in these various channels, and, by so doing, it acts to seal the associated joints between the contacting surfaces, such sealing or closing action being increased or augmented 55 by the gradual deposit and accumulation of carbon on the surface of the member which the groove faces and covers.

55 It is immaterial in which of the two members bearing on one another the groove or channel is present, for example, it could just as well be in the end surface of the inner cylinder as in the associated sealing-ring.

60 The refrigerating or cooling effect of the incoming, gaseous, fuel mixture on the di-

vided, sealing-ring, inlet-port strut or bridge prevents the development of a temperature high enough to be conducive to the formation of carbon, which, if it occurred in substantial measure to fill the gap in the ring 70 joint, would not permit proper expansion and contraction of the ring, especially under high speed operating conditions, with probable resultant seizure.

75 By placing the gap or joint in such intake-port strut there is only a soft carbon formation causing no damage and not preventing ring growth.

80 From the foregoing, it will be apparent that the sealing-ring, by reason of its inherent inclination to enlarge, supplemented by the gas pressure in the cylinders acting on it and tending to expand it, is forced outwardly against the two valves, pressing them firmly against the inner surface of the outer cylinder and maintaining a gas pressure tight 85 relation therewith.

85 The sealing-ring expands and contracts in minor degree under varying heat and cold conditions and the construction is such as 90 to render this possible and at the same time prevent blow-by through the various joints.

90 The sealing-ring during the performance of its important functions is held down to its work by the hold-down ring which in turn 95 is forced downwardly by the variable gas pressure itself acting on its ledge and by the plurality of short springs.

95 Escape of gas under pressure between the hold-down ring and the cylinder-head is 100 avoided by the gas-pressure enlarged sealing-reed.

100 As has been indicated, none of the parts of the exhaust-ports are strutted or bridged, and, consequently, a free and unobstructed passage of the hot, exhaust gases occurs with the result that the cylinder is more thoroughly and completely scavenged or freed of exploded gases than has heretofore been usual with resultant less dilution of the next, succeeding, gaseous, fuel-mixture charge, hence producing greater power in the engine and obtaining a substantially improved economy 105 in fuel consumption.

110 Such efficient, prompt and more complete discharge of the hot gases of combustion reduces the heating effect of such gases in the engine and lessens the destructive action of the gases on the margins or edges of the exhaust-ports in the cylinder, valves and sealing-ring.

115 The absence of any obstructing strut or bridge in the various exhaust-ports of the several elements, particularly the ports of the exhaust-valve and sealing-ring, is considered of major importance, because, if such retarding or impeding strut or bridge be employed, it becomes more highly heated than the other portions of the same member causing such a distortion of the member as is 120 125 130

likely to allow leakage of the gases under pressure.

For example, if such a barrier or bridge be employed in the exhaust-port of the sealing-ring, it causes that particular part of the ring to expand up and down more than the other portions of the ring, and hence such distorted shape of the ring renders it difficult, if not impossible, to keep the joints between it and the inner cylinder and the hold-down ring properly sealed.

Such detrimental warping or deformation is all the more likely to occur when such a bridge is used, because it is always in the direct path of the hot discharging gases, whereas the other parts of the ring are in contact with the valves which assists in conducting the heat away from them, hence keeping them cooler than the highly heated bridge.

20 The absence of strut in the port of the exhaust-valve eliminates or avoids heat distortion which tends to result in an improper seal between the inner surface of the valve and the outer face of the sealing-ring.

25 The omission of exhaust-port struts excludes unnecessary heat-accumulating means and the whole performance of the engine is cooler by reason of the absence of the heat absorbing bridge and this allows the maintenance of a better oil film on the ring and valve.

In this connection, it should be borne in mind, that, even with no strut in the exhaust-port of the sealing-ring, the latter cannot expand so as to catch on the edges of the valve-port, because the upper part of the sealing-ring is always above the valve-port and hence prevents undue enlargement of the sealing-ring as a whole, including that part which operates with the valve-port.

40 Turning now to a consideration of the valve-operating mechanisms, it will be observed from what precedes, that the stroke of the exhaust-valve with its wider port is longer than that of the inlet-valve with its narrower port.

The valve opening area increases more in proportion than the increase in the length of valve stroke.

50 The advantage of a short valve stroke, as in the case of the inlet-valve, is the low valve inertia, whereas the benefit of the long stroke is the larger port opening area with more rapid opening.

55 Thus the one advantage is present in the exhaust-valve and the other in the inlet-valve.

If the point of attachment of the connecting-rod with the valve were exactly above the center or axis of the eccentric or crank-shaft operating the valve, the curve representing the opening and closing of the valve would be symmetrical, but by offsetting these two points, the curve has a relatively steep angle on one side and a comparatively flat angle on the other side, and the directions of rotation

of the two eccentric shafts are so chosen, as illustrated, to take advantage of this irregular or immethodical curve to advantageously cause the intake-valve to open faster than it closes and the exhaust-valve to close faster than it opens.

It is desirable to have the intake-valve open fully either before, or exactly at the time of, maximum downward piston velocity, and, if the complete opening of the valve is subsequent to such greatest piston speed, an objectionable wire-drawing effect on the gases through the port occurs, causing a harmful retardation of fuel flow into the cylinder.

Such an occurrence at slow engine speeds is not important, but at its higher speeds, it is particularly objectionable, materially reducing the power which the engine is capable of developing.

By reason of the early full opening of the intake-valve above specified, the gaseous fuel is permitted to flow into the cylinder under unusually favorable conditions for the production of power at higher speeds, particularly as compared with the action of the usual Knight engine.

It is desirable to have the opening of the valves conform more or less closely to the piston velocities and with this construction the intake-valve opens quickly which coincides with the rapid downward movement of the piston during the first half of the induction stroke, the exhaust-valve opening slowly which corresponds to the gradual travel of the piston during the first half of the exhaust stroke.

The exhaust-valve is favorably operated to retain the working pressure in the cylinder as long as possible with a certain breadth of timing and still have a completely or adequately scavenged cylinder at the top of the piston stroke.

Such result is obtained easily by the offsetting specified to secure a slow opening but quick closing of the exhaust-port.

Other forms of sealing-reeds are depicted in Figures 6 to 8 inclusive and in the structure of Figure 6, a reed cage 81 fitted tight on the cylinder-head holds a number of superposed, circular, flexible reeds 82, 82 bearing on the hold-down ring, in that of Figure 7 a single, flexible, metal ring 83 of inverted U-shape is employed, whereas in the application of Figure 8, a cage 84 and associated spacing-rings 85 hold together a number of separated, elastic reeds 86, 86.

These modified structures operate in much the same way as the preferred construction and seemingly require no further description.

In all of the various forms of sealing-reeds specified, it is desirable, in order to obtain maximum functioning efficiency of the engine, to have the cylinder-head, the sealing-reed and the hold-down ring made of metals of substantially the same coefficient of heat

expansion and contraction, so that under all circumstances the sealing-reed will maintain proper gas pressure tight relation with the hold-down ring without danger of excessive outward pressure of the reed which might prevent the springs 67 from operating properly.

The invention is in no way confined to the especial embodiments set forth and many changes may be incorporated in the structures without abandonment of any of the substantial advantages accruing from the use of the invention, as defined by the appended claims.

I claim:

1. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said outer cylinder ports, arcuate valves slid-able between said outer cylinder and said inner cylinder and sealing-ring to control said ports, means to reciprocate said valves, a piston reciprocatory in said cylinder, a hold-down ring bearing on the top of said sealing-ring, and a sealing-reed between said cylinder-head and said hold-down ring having a flexible portion engaging the inner surface of said hold-down ring subjected to the gas pressure in said cylinders which forces such portion against said hold-down ring tending to maintain a gas pressure tight seal between them.

2. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said outer cylinder ports, arcuate valves slid-able between said outer cylinder and said inner cylinder and sealing-ring to control said ports, means to reciprocate said valves, a piston reciprocatory in said cylinder, a hold-down ring bearing on the top of said sealing-ring, and a sealing-reed between said cylinder-head and said hold-down ring having an outwardly-flaring flexible flange engaging the inner surface of said hold-down ring subjected to the gas pressure in said cylinders which forces such flange against said hold-down ring tending to maintain a gas pressure tight seal between them.

3. In an internal-combustion engine, the combination of an outer cylinder having inlet and exhaust ports, a head for said cylinder, a second cylinder inside of and spaced inwardly away from said outer cylinder, a longitudinally-split expansible sealing-ring bearing endwise on said inner cylinder and having ports in substantial register with said outer cylinder ports, arcuate valves slidable be-

tween said outer cylinder and said inner cylinder and sealing-ring to control said ports, means to reciprocate said valves, a piston reciprocatory in said cylinder, an endless hold-down ring bearing endwise on the top of said sealing-ring, and an endless sealing-reed between said cylinder-head and said hold-down ring having a flexible portion engaging the inner surface of said hold-down ring subjected to the gas pressure in said cylinders which forces such portion against said hold-down ring tending to maintain a gas pressure tight seal between them.

4. In an internal-combustion engine, the combination of an outer cylinder having inlet and exhaust ports, a head for said cylinder, a second cylinder inside of and spaced inwardly away from said outer cylinder, a longitudinally-split expansible sealing-ring bearing endwise on said inner cylinder and having ports in substantial register with said outer cylinder ports, arcuate valves slidable between said outer cylinder and said inner cylinder and sealing-ring to control said ports, means to reciprocate said valves, a piston reciprocatory in said cylinder, an endless hold-down ring bearing endwise on the top of said sealing-ring, resilient means tending to force said hold-down ring towards said sealing-ring, and an endless sealing-reed between said cylinder-head and said hold-down ring having a flexible portion engaging the inner surface of said hold-down ring subjected to the gas pressure in said cylinders which forces such portion against said hold-down ring tending to maintain a gas pressure tight seal between them, said sealing-reed being located to prevent the gas pressure in said cylinders from reaching said resilient means.

5. In an internal-combustion engine, the combination of cylinder-means having inlet and exhaust ports, a head for said cylinder-means, a sealing-ring bearing endwise on said cylinder-means and having ports in substantial register with said inlet and exhaust ports, valves controlling said ports slidable between said cylinder-means and said sealing-ring, means to reciprocate said valves, a hold-down ring bearing endwise on the top of said sealing-ring, and a sealing-reed between said cylinder-head and said hold-down ring having a flexible portion engaging the inner surface of said hold-down ring subjected to the gas pressure in said cylinders which forces such portion against said hold-down ring tending to maintain a gas pressure tight seal between them.

6. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having a single exhaust port in

- substantial register with the exhaust port of said outer cylinder and a bridged inlet-port in substantial register with the inlet-port of said outer cylinder with said bridge arranged longitudinally of the sealing-ring, valves controlling said cylinder and sealing-ring ports slideable between said outer cylinder and said inner cylinder and sealing-ring, means to reciprocate said valves, and means 5 acting on the upper end of said sealing-ring tending to press it down against said inner cylinder with greater force on the bridged inlet-port portion of the sealing-ring than on the unbridged exhaust-port part thereof.
7. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciprocatory in said inner cylinder, arcuate valves controlling said ports slideable between said outer cylinder and said inner cylinder and sealing-ring, means to reciprocate said valves, means to hold said sealing-ring to its bearing on said inner cylinder, and means to lubricate said valves and piston, one at least of the contacting surfaces of said sealing-ring and inner cylinder having a channel lubricant in which tends to seal the joint between the surfaces against the escape of gas under pressure.
8. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having a single exhaust-port in substantial register with the exhaust-port of said outer cylinder and a bridged inlet-port in substantial register with the inlet-port of said outer cylinder with said bridge arranged longitudinally of the sealing-ring, valves controlling said cylinder and sealing-ring ports slideable between said outer cylinder and said inner cylinder and sealing-ring, means to reciprocate said valves, a hold-down ring bearing endwise on said sealing-ring, and means acting on the upper end of said hold-down ring tending to press it down against said sealing-ring with greater force 35 on the bridged inlet-port portion of the sealing-ring than on the unbridged exhaust-port part thereof.
9. In an internal-combustion engine, the combination of cylinder-means having inlet and exhaust ports, a head for said cylinder-means, a sealing-ring bearing endwise on said cylinder-means and having a single exhaust-port in substantial register with the exhaust-port of said outer cylinder and a bridged inlet-port in substantial register with the inlet-port of said outer cylinder with said bridge arranged longitudinally of the sealing-ring, valves controlling said cylinder and sealing-ring ports slideable between said outer cylinder and said inner cylinder and sealing-ring, means to reciprocate said valves, and means to reciprocate said valves, means to hold said sealing-ring to its bearing on said inner cylinder, and means to lubricate said valves and piston, one at least of the contacting surfaces of said sealing-ring and inner cylinder having a channel lubricant in which tends to seal the joint between the surfaces against the escape of gas under pressure.
10. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciprocatory in said inner cylinder, arcuate valves controlling said ports slideable between said outer cylinder and said inner cylinder and sealing-ring, means to reciprocate said valves, means to hold said sealing-ring to its bearing on said inner cylinder, and means to lubricate said valves and piston, one at least of the contacting surfaces of said sealing-ring and inner cylinder having a channel lubricant in which tends to seal the joint between the surfaces against the escape of gas under pressure.
11. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciprocatory in said inner cylinder, arcuate valves controlling said ports slideable between said outer cylinder and said inner cylinder and sealing-ring, means to reciprocate said valves, means to hold said sealing-ring to its bearing on said inner cylinder, and means to lubricate said valves and piston, one at least of the contacting surfaces of said sealing-ring and inner cylinder having a channel lubricant in which tends to seal the joint between the surfaces against the escape of gas under pressure.
12. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciprocatory in said inner cylinder, arcuate valves controlling said ports slideable between said outer cylinder and said inner cylinder and sealing-ring, means to reciprocate said valves, means to hold said sealing-ring to its bearing on said inner cylinder, and means to lubricate said valves and piston, one at least of the contacting surfaces of said sealing-ring and inner cylinder having a channel lubricant in which tends to seal the joint between the surfaces against the escape of gas under pressure.

n said inner cylinder, and means to lubricate said valves and piston, said sealing-ring 1 its outer surface in contact with said valves aying channels both above and below its orts lubricant in which tends to seal the joint between the surfaces against escape of as under pressure.

13. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciproca- 70 ry in said inner cylinder, arcuate valves controlling said ports slidable between said outer cylinder and said inner cylinder and sealing-ring, means to reciprocate said valves, means to lubricate said valves and piston, and a hold-down ring bearing on the upper end of said sealing-ring, one at least of the contacting surfaces of said hold-down ring and sealing-ring having a channel lubricant in which tends to seal the joint between the surfaces against the escape of gas under pressure.

14. In an internal-combustion engine, the combination of an outer cylinder having inlet and exhaust ports, a head for said cylinder, a second cylinder inside of and spaced inwardly away from said outer cylinder, a sealing-ring bearing endwise on said inner cylinder and having ports in substantial register with said cylinder ports, a piston reciproca- 75 ry in said inner cylinder, arcuate valves controlling said ports slidable between said outer cylinder and said inner cylinder and sealing-ring, means to reciprocate said valves, means to lubricate said valves and piston, and a hold-down ring bearing on the upper end of said sealing-ring, one at least of the contacting surfaces of said sealing-ring and inner cylinder and one at least of each pair of contacting surfaces of said sealing-ring and valves and one at least of the contacting surfaces of said hold-down ring and said sealing-ring having a channel lubricant in which tends to seal the joint between the surfaces against the escape of gas under pressure.

15. In an internal-combustion engine, the combination of an outer cylinder having inlet and exhaust ports, a head for said cylinder, a second cylinder inside of and spaced inwardly away from said outer cylinder, a piston slidable in said inner cylinder, a sealing-ring bearing on an end of said inner cylinder and having ports in substantial register with said cylinder ports, arcuate valves controlling said ports and slidable between said outer cylinder and said inner cylinder and sealing-ring, means to reciprocate said valves, a hold-down ring bearing on said sealing-ring, and a flexible cover over the joint between, and adapted to be flexed by the gas pressure

in the cylinders outwardly against, said hold-down ring and said sealing-ring.

16. In an internal-combustion engine, the combination of an outer cylinder having inlet and exhaust ports, a head for said cylinder, a second cylinder inside of and spaced inwardly away from said first cylinder, a piston slidable in said inner cylinder, a sealing-ring bearing on an end of said inner cylinder and having ports in substantial register with said cylinder ports, arcuate valves controlling said ports and slidable between said outer cylinder and said inner cylinder and sealing-ring, means to reciprocate said valves, and a flexible cover over the joint between, and adapted to be flexed by the gas pressure in the cylinders outwardly against, said inner cylinder and sealing-ring. 80

17. In an internal-combustion engine, the combination of a cylinder having port means, a head for said cylinder, a piston slidable in said cylinder, a connecting-rod joined to said piston, means controlling said port means, and means to seal the gas pressures in said cylinder including a flexible sealing member subjected to, and capable of flexing under, the gas pressure in said cylinder to confine such pressure therein against leakage between said head and cylinder. 85

18. In an internal-combustion engine, the combination of a cylinder having port means, a head for said cylinder, a piston slidable in said cylinder, a connecting-rod joined to said piston, means controlling said port means, and means to seal the gas pressures in said cylinder including a transversely-flexible sealing-ring subjected to, and capable of flexing under, the gas pressure in said cylinder to confine such pressure therein against leakage between said head and cylinder. 95

19. In an internal-combustion engine, the combination of an outer cylinder having inlet and exhaust ports, an inner cylinder inside of and spaced inwardly away from said outer cylinder, a pair of valves between and slidable lengthwise of said cylinders, means to reciprocate said valves, a head for said outer cylinder, a circumferentially expansible sealing-ring inside of and adapted to press outwardly against said valves and bearing endwise on said inner cylinder, said sealing-ring having an intake-port in substantial register with said outer cylinder inlet-port and a single unbridged exhaust-port in substantial register with said outer cylinder exhaust-port, means to prevent gas pressure leakage between said sealing-ring and said inner cylinder and between said sealing-ring and said cylinder-head while permitting circumferential expansion of said sealing-ring against said valves, a piston reciproca- 110

combination of an outer cylinder having inlet and exhaust ports, an inner cylinder inside of, spaced inwardly away from, and having its upper end lower than said ports of
5 said outer cylinder, a pair of valves between and slidable lengthwise of said cylinders, means to reciprocate said valves, a head for said outer cylinder, a circumferentially expansible sealing-ring inside of and adapted
10 to press outwardly against said valves and bearing endwise on said inner cylinder, said sealing-ring having an intake-port in substantial register with said outer cylinder inlet-port and a single unbridged exhaust-
15 port in substantial register with said outer cylinder exhaust-port, resilient means acting on said sealing-ring longitudinally to prevent gas pressure leakage between said sealing-ring and said inner cylinder and between
20 said sealing-ring and said cylinder-head while permitting circumferential expansion of said sealing-ring against said valves, a piston reciprocatory in said inner cylinder, a shaft, and means operatively connecting said
25 piston and shaft.

In witness whereof I have hereunto set my hand.

RALPH L. SKINNER.
